UNITED STATES PATENT OFFICE.

EDGAR M. PALMER, OF HARTFORD, CONNECTICUT.

WOODWORKING MACHINE.

Application filed September 16, 1920. Serial No. 410,655.

To all whom it may concern:

Be it known that I, EDGAR M. PALMER, a citizen of the United States, and a resident of Hartford, in the county of Hartford, State of Connecticut, have invented certain new and useful Improvements in Woodworking Machines, of which the following is a specification.

The present invention relates to a machine of the character described. In the present instance, the various features of the invention are disclosed, for illustrative purposes, as being employed for grooving the opposing surfaces of the arms of clothespins or the like to which use it is particularly adapted. The aim of the invention is to provide a machine of this sort which is simple in construction and efficient in operation.

Referring to the drawings, wherein one embodiment which the invention may take is illustrated,

Fig. 1 is a top view, portions being broken away for the purpose of illustration.

Fig. 2 is a side view in vertical section substantially on line 2—2 of Fig. 3.

Fig. 3 is a front view, and

Fig. 4 is a view of a clothes-pin showing the manner in which the arms thereof are grooved in the present machine.

Referring to the drawings in detail, *a* designates a frame of any suitable construction; *b*, a holder thereon; *c*, a tool or tools passing through the holder; *d*, *e*, clamping members or levers for forcing the arms of clothes-pins or the like against the tool *c*, and *f*, means for ejecting clothes-pins from the holder. The holder *b*, which is mounted on the top of the frame *a* has a through bore or socket 10 of a size adapted to receive the arms of a clothes-pin *x* as shown in dotted lines Fig. 1. To each side of the socket or bore 10 and opening thereinto is a recess or slot 11 in which the clamping members *d*, *e* are pivoted. In the present instance, the holder comprises a plate 12 secured to the top of the frame *a* and a second and smaller plate 13 secured to the plate 12 in any suitable manner as by means of screws 14. If desired, the holder may be formed of one piece or otherwise.

16, 17, denote brackets respectively located above and below the holder and having alined slide-ways 18 in which reciprocate blocks 19 to which the opposite ends of the

tools *c* are connected. These tools, in the present instance, are shown as being in the form of round files. The blocks 19 and the files *c* carried thereby are reciprocated in any suitable manner, for instance by a crank 60 and pitman 21. The files *c* extend at right angles through the bore 10, the walls of the latter being slotted at 22 to permit of this arrangement.

The clamping member *d* is pivoted at its rear end and the clamping member *e* between its ends, thus providing levers of the second and first classes respectively, the gripping portions or jaws 23 of which are adapted to extend into the bore 10 and engage the arms of the clothes-pin. The outer ends of the clamping members or levers *d*, *e*, are connected by a rod 24 so that they are operated in unison upon depression of an operating lever 25 to one arm of which the member *a* is connected by means of a link 26. To move the members *d*, *e*, out of clamping position after the operating lever 25 is released, a tension spring 27 is connected between the member *d* and a fixed part of the holder. If desired, a rod 28 connected at its upper end to the operating lever 25 and at its lower end to a foot treadle (not shown) may be provided so that the clamping members can be operated either by hand or by foot.

Within and adjacent the forward end of the bore 10 is a stop 29 so positioned that it will engage in the crotch between the arms of a clothes-pin so as to limit the extent to 90 which the latter is moved into the bore. 31 designates a lever pivoted at 32 and having a depending projection 33 adapted to engage a clothes-pin within the bore and securely hold the same against movement while it is being grooved by the files. This lever may have a counter weight 34. In the present instance, it is connected to the operating lever 25 by means of a link 35 so that the clamping members *d*, *e*, and the lever 31 are 100 operated in unison.

For the purpose of ejecting the clothespins, after they are released by the clamping members, a plunger 40 is slidably fitted in the rear end of the bore 10 and is urged by means of a spring, for instance a rubber band 41, inwardly of the bore. The plunger is provided with projections 42 which work in the slots 22 so that the plunger does not rotate.

The operation of the device will be readily understood. To groove a clothes-pin, the arms of the latter are inserted into the bore 10 so that they straddle the files *c* which are 5 constantly reciprocated by the crank and pitman 21. The operating lever 25 is then depressed causing the clamping members *d*, *e*, to force the arms of the clothes-pin against the reciprocating files and at the 10 same time the lug 33 is brought into engagement with the top of the clothes-pin. After the arms of the clothes-pins have been grooved to the desired extent, the operating lever 25 is released whereupon the spring 27 15 will throw the clamping members out of clamping position and raise the lever 31 leaving the clothes-pin free to be ejected from the holder by the spring pressed plunger 40. With the use of the present 20 machine, the arms of the clothes-pin are grooved as at *y*, referring to Fig. 4.

It is, of course, obvious that my invention is susceptible of various modifications and changes which are within the spirit of the 25 invention without departing from the scope of the following claims, it being understood that the present disclosure of my invention is by way of illustration only and it is not to be taken as restrictive of my conception.

30 I claim as my invention:—

1. In a machine of the character described, a holder adapted to receive a clothes-pin or the like, a tool extending through said holder, and means for moving the arms of 35 the clothes-pin towards each other and against said tool during operation upon said arms.

2. In a machine of the character described, a reciprocating tool, a pair of clamping arms 40 constantly positioned, one to each side of said tool adapted for simultaneously clamping the work and moving the same into engagement with the tool, and means for moving the clamping members toward the tool.

45 3. In a machine of the character described, a holder adapted to receive the arms of a bifurcated article, a longitudinally reciprocating file passing through said holder, and means constantly arranged at opposite sides 50 of the file for moving the arms of the articles against said file during the filing operation.

55 4. In a machine of the character described, a holder, a reciprocating tool, a pair of clamping members constantly arranged, one to each side of said tool, means for moving said clamping members towards one another 60 to force the parts of the work against said tool, and automatically operating means for withdrawing said clamping members from operative position.

65 5. In a machine of the character described, a reciprocating file, a pair of clamping members constantly positioned, one to each side of said file and adapted to force the

arms of an article straddling said file against said file, a connection between said levers, and an operating handle connected to said levers for forcing the same towards one another during the filing operation.

70 6. In a machine of the character described, a reciprocating tool, a holder adapted to receive an article with parts thereof straddling said tool, a pair of clamping members constantly positioned, one to each side of 75 said tool and adapted to force the articles thereagainst during operation upon said article, one of said levers being of the first class and the other of the second class, a connection between said levers, and an operating lever for actuating said levers.

7. In a machine of the character described, a holder having a socket adapted to receive the arms of bifurcated articles, a tool passing at right angles through said socket, a 80 clamping member carried by said holder to each side of said socket and adapted to extend thereinto for forcing the arms of the articles against said tool, and operating means for said clamping members.

8. In a machine of the character described, a holder adapted to receive articles to be operated upon, a reciprocating tool, a pair of clamping members constantly positioned one to each side of said tool, means for urging 90 said clamping members towards one another to move the articles against said tool during operation upon said articles, and means for holding said articles steady within said holder.

9. In a machine of the character described, a holder having a socket adapted to receive the articles to be operated upon, a reciprocating tool extending across said socket, a pair of clamping members carried by said 105 holder and adapted to force the straddling portions of the articles against said tool, means for preventing the articles from moving in the direction of movement of said tool, and connections between said clamping members and last mentioned means whereby the same are operated in unison.

10. In a machine of the character described, a holder having a socket adapted to receive the arms of a bifurcated article, a 110 tool for grooving the opposing faces of the arms, clamping means for forcing the arms into engagement with the tool, and means rendered operative by engagement with the article for ejecting the articles from said 115 socket when the clamping means are released.

11. In a machine of the character described, a holder having a socket adapted to receive the arms of bifurcated articles, a tool 120 extending across said holder, clamping members for forcing the arms of the articles towards each other and against said tool, and a spring pressed plunger for ejecting the articles from said socket when the clamping 125 means are released.

members are withdrawn from clamping position.

12. In a machine of the character described, a holder having a socket adapted to receive the arms of bifurcated articles, a lug in said socket for limiting the movement of the articles into said socket, a tool extending across said socket and means for forcing the arms of the articles against said tool.

13. In a machine of the character described, a holder, a reciprocating file extending through said holder, means for moving the portions of an article within said holder

and straddling said file against said file during the filing operation. ¹⁵

14. In a machine of the character described, a holder having a socket adapted to receive the arms of a bifurcated article, a reciprocating file for grooving the opposing faces of the arms, clamping means for moving the arms into engagement with the file during the filing operation, and means for ejecting the articles from said socket through the same end through which they are inserted into the socket.

EDGAR M. PALMER.
